SPRAY GUN

Alfred W. Smart, Rockville Centre, N. Y., assignor to Olsenmark Corporation, a corporation of New York

Application October 4, 1928, Serial No. 310,417

17 Claims. (Cl. 299—140.1)

My invention relates to spray guns and more particularly to a gun adapted to project a jet or spray of material therefrom and may or may not include an arrangement for projecting a jet of air therefrom independently of or conjointly with the material jet.

In the embodiment of my invention shown and described hereinafter the gun is especially adapted to be used in the art of painting.

10 In the process of painting by the spray method, the gun or tool is connected to a tank of liquid, usually under pressure, and also to a source of air under pressure. The liquid is ejected under the control of a trigger that is actuated by an operator.

15 In painting various sizes of surfaces it becomes desirable to alternate between a narrow or round jet and a wide or flat jet. Heretofore, in guns of the type referred to and in order to accomplish the results desired, the mechanism has been cumbersome, expensive and requires a variety of adjustments that necessitated stopping the operation of the gun.

20 Furthermore, where an article was to be painted in two or more colors it has been necessary for the operator to have two or more complete guns and attachments, a separate one for each color.

25 It is one object of my invention to provide a gun of the type referred to wherein the change from a narrow jet or spray to a wide jet or spray and vice versa is made automatically at the election of the operator.

It is another object of my invention to provide a spray gun having a fluid valve that is detachably connected to the body of the gun.

30 It is a further object of my invention to provide a system wherein tanks of various colors may be equipped with liquid valves that may be 35 interchangeably connected into my improved holder or gun.

It is a still further object of my invention to provide a spray gun in which an operator by actuation of the trigger can obtain selectively a jet 40 of air without liquid, a narrow jet of atomized liquid, and a wide jet of atomized liquid.

It is a still further object of my invention to provide a spray gun of the character described having relatively few parts in contact with the 45 liquid and each of these parts being removable for ready cleaning thereof.

It is a still further object of my invention to provide a spray gun having an air valve and a fluid valve, each of the removable cartridge type.

50 It is a still further object of my invention to

provide a holder wherein the fluid and air valves are in axial alignment.

It is a still further object of my invention to provide means for simultaneously adjusting the fluid and air valves so as to regulate the quantity of liquid fed to the sprays or jets. 5

It is a still further object of my invention to provide an arrangement for securing a wide spray in which a drop in pressure occurs at the outlet for the atomizing air streams so as to prevent 10 the creation of a vortex that would permit accumulations of paint near or about the spray openings.

It is a still further object of my invention to provide a gun that is well balanced when connected for use. 15

It is a still further object of my invention to provide a spray gun comprising a holder from which all other parts are readily detachable to facilitate repairs and replacements. 20

It is a still further object of my invention to provide a spray gun wherein the change over from a narrow or round jet to a wide or fan jet is accomplished by operation of a two-way air valve. 25

My invention will be best understood by reference to the following specification and the accompanying drawings wherein—

Fig. 1 is a side elevation of my improved gun; 30
Fig. 2 is a series of tanks equipped with my improved fluid valve and illustrating my improved method and system of operation;

Figs. 3, 4 and 5 are vertical, central sections of my improved gun illustrating the respective positions of the operating trigger, valves, etc., 35 for securing the various jets desired, parts of the gun being broken away to facilitate illustration;

Fig. 6 is a detail longitudinal section on the line C—C of Fig. 3; 40

Fig. 7 is a cross section of the air valve and its mounting, on the line B—B of Fig. 3;

Fig. 8 is a cross section of the air valve and its mounting, on the line A—A of Fig. 3;

Fig. 9 is a front view of the distributor with the fluid valve in position, parts being broken away to facilitate illustration; 45

Fig. 10 is a detail vertical section of the distributor and retaining ring;

Fig. 11 is a rear view thereof; 50

Fig. 12 is a detail view of a portion of the mounting hood for the fluid valve; and

Fig. 13 is a vertical section on the line D—D of Fig. 5, the fluid valve being omitted, and parts being broken away to facilitate illustration. 55

General arrangement

Referring to Fig. 1, my improved holder comprises a body portion 21 and a handle portion 22, particularly shaped to accommodate the grip of the hand of an operator and provided with guiding projections or rests 23 and 24. The handle is detachably secured to the body portion in any well known manner.

Mounted at the rear of the body portion 21 and removable therefrom is an air valve 25, which is connected, through the handle 22, to the nipple 26 that is screw threaded so as to receive the connecting junction of an air hose leading from a supply of compressed air.

15 Detachably mounted in the forward portion of the body 21 is a fluid valve 27 having a screw threaded nipple 28 adapted to receive the connecting junction 29 (Fig. 2) that is secured to a hose 31 which is in turn connected to a tank 32 of paint or other fluid. The fluid in the tank 32 may be under pressure which may be supplied in any well known manner. The fluid valve 27 is mounted under and practically enclosed by the hood 30, which is integral with the holder 21, and open on its under side only.

The forward end of the gun has removably mounted thereon a spray tip or distributor 33 that is also separable from the fluid valve 27 and independent thereof.

30 Extending between the valves 25 and 27 is a connecting link 34 having at each end thereof knurled nuts 35 and 36. The nut 35 is not removable from the shaft 34, but the nut 36 is adjustable therealong and may be termed a regulator for the fluid valve.

Extending above the body portion 21 and secured thereto or integral therewith is a projection 37 which terminates in a ring or hook 38 by which the gun may be suspended whenever the same is not in use.

40 Detachably mounted upon the projection 37 are two depending arms 39 which terminate in and may be integral with a trigger 41 which is located below the body portion 21 and convenient to the handle grip 22. The trigger 41 has an upwardly extending projection 42 which extends into the connecting link 34 and is the operating element of the trigger for initiating and controlling the action of the gun.

50 All of the foregoing parts have been referred to generally in their various locations. The details of each as well as the detailed mode of operation will be described hereinafter.

55 At this time it is desired to direct attention to the fact that I have provided a new system of operation in a plant equipped with my spray guns. Such a plant will have a plurality of the liquid or paint tanks 32, holding paints of different colors or different materials and having the material under pressure therein, and each having a hose 31 connected thereto. Heretofore it has been necessary for such a plant to either have a complete gun attached to each hose 31 and to provide 60 some extra valve arrangement in the hose so that the gun could be removed therefrom for cleaning and repairing, or some other more laborious arrangement was necessary.

With my improved system, each hose has 65 detachably connected thereto, in place of the usual valve, one of my fluid valves 27 which are adapted to be left attached to the respective hoses. When an operator desires to change from one color to another, or from a stain to a varnish, etc., it is 70 only necessary for the operator to unloosen the

fluid valve 27 from the holder 21 and attach the fluid valve 27 that is affixed to the hose of the tank of the particular color or material which he desires to next use. It is not necessary to change any other part of the gun, to continue 5 operation, after the new fluid valve 27 has been inserted in the holder. This convenience of quickly shifting from one color to another and permitting the continued use of the same gun has not heretofore been possible.

10

Air valve

The air valve is of the cartridge type and comprises a body portion 51 which is externally screw threaded as indicated at 52 to cooperate with a screw threaded aperture in the rear of the body portion 21 of the holder. The body 51 is cylindrical and hollow. The forward reduced portion 53 thereof is also hollow and is adapted to constitute the support and guide for a plunger 54. The hollow rear portion forms an air chest 55. Intermediate the front and rear portions, the body 51 is tapered to cooperate with a tapered portion 56 of the aperture in the body portion 21 of the holder. It is against this tapered seat that the valve is forced when the valve is screwed into place, to thus operatively position the valve.

15 In its tapered portion, the body 51 is provided with two sets of ports 57 and 58 each set being joined by an annular channel and adapted to be sealed from each other when the valve is in position. Immediately to the rear of the tapered portion is an annular channel 59 having a set of ports 61 communicating therewith. The channel 59 also begins immediately in the rear of the 25 tapered portion 56 of the holder 21.

20 On the interior, the chest 55 is formed with a reduced portion having a tapered seat 62 against which seats the tapered valve 63 that is integral with the plunger 54. It will be noted that the 30 ports 61 communicate with the chest 55 in back of the valve head 63 and therefore are always in open communication therewith. The ports 58 communicate with the chest 55 on the side of the seat 62 that is closed by the head 63. The ports 35 57 are located forward of the ports 58 and are brought into communication with the chest 55 only when the plunger 54 is moved a sufficient distance to bring the channel 64 therein into a 40 position where it communicates with the ports 50 57 and also with the chest 55.

45 The plunger 54 is spring pressed into a closed position by the spring 66 which engages with the rear of the head 63 and also with the forward face of a closing plug 67 for the chest 55. The 55 interior of the chest 55 is screw threaded as is the forward portion of the plug 67 so that the plug is removable therefrom at will for cleaning of the valve and other purposes.

50 The plug 67 is hollow and provided in its forward face with an aperture 68 against which a plate 69 rests to close the same. The plate 69 is spring pressed into its closed position by means of a spring 71 that engages the plate and also the forward face of a screw cap 72. When cap 72 is screwed into position with the plate 69 and spring 71, the plug 67 is a complete unit, ready for insertion in the valve body to close the same.

55 When the valve unit is inserted in the body portion 21 of the holder, the channels of the ports 57 and 58 respectively register with ports 73 and 74 (shown in Figs. 8 and 7) in the body portion 21. The ports 73 and 74 respectively communicate with longitudinal passages 75 and 76 extending through the body of the gun for pur- 60 65 70 75

poses to be hereinafter more fully described. It will be noted that the passages 75 and 76 are parallel with each other.

As illustrated in Fig. 3, the channel of the ports 61 is in communication with a port 77 which extends downwardly into communication with the upper open end of a pipe 78 that is screwed into the body portion 21 of the holder. At its lower end the pipe 78 communicates with the nipple 26 shown in Fig. 1. Hence communication is established through the handle between a source of compressed air and the valve chest 55. The handle could be made air tight, if desired, to thus eliminate the pipe 78.

When the valve 25 is assembled in position, the forward end thereof projects beyond the body of the holder and is adapted to receive in sliding engagement the regulating nut 36, the construction and function of which will be described hereinafter. It is sufficient to call attention to the fact that the end 42 of the trigger 41 is forward of the regulating nut 36 and that the forward end of the valve plunger 54 extends through the regulating nut 36 and into the vicinity of the trigger 41 in position to be engaged by the upper end 42 thereof.

In the normal position the valve is closed so that no air is admitted to the ports 57 and 58 and communicating passages 75 and 76, the valve head 63 being against the seat 62. However, the ports 61 are not closed so that air is present in the valve chest 55. It will also be noted that the rear end of the plunger 54 is spaced away from the plate 69.

The first movement of the trigger 41 shown in dotted lines in Fig. 3 will cause the end 42 to engage the end of the plunger 54. If the trigger 41 is compressed slightly or to the point where the end 42 contacts with the forward end of the nut 36, the valve head 63 will be moved from off its seat 62 a short distance, to admit a supply of air to the ports 58 and communicating passage 76, for the purpose to be hereinafter described. This may be termed the first operative position of the air valve, and the regulating nut a stop for determining the amount of movement of the plunger for its first position. It may be pointed out that this movement is not sufficient to carry the rear end of the plunger 54 into engagement with the plate 69.

The second operative position of the air valve is illustrated in Fig. 4. By comparison with Fig. 3, it will be noted that the trigger 41 has been moved so as to move the plunger 54 further to the rear to establish direct communication between the ports 61 and 58 so that a full supply of air under pressure is admitted to the passage 76. This movement has also carried with it the regulating nut 36, and carried the rear end of the plunger 54 into contact with the plate 69. Thus the plate 69 may be termed the stop for determining the position of the parts for the second operative position of the air valve.

The third operative position is illustrated in Fig. 5. In this position, it will be noted that the rear end of the plunger 54 has entered the plug 67 and caused the plate 69 to compress the spring 71. In this position, the channel 64 has established a path of communication between the chest 55 and the ports 57 and communicating passage 75, whereby air is admitted to the passage 75. The passage 76 also has air supplied thereto in this position.

The purposes of these positions in the operation 75 of the gun will be explained hereinafter.

Fluid valve

The fluid valve comprises a body portion 81 that is cylindrical and hollow. The rear portion is screw threaded as indicated at 82. The forward portion is tapered and comprises two sections 83 and 84 between which is an annular channel. The section 83 is provided with a pair of transverse grooves 85 communicating with the channel and with the exterior. Beyond the tapered portion 83 is a nozzle 86 that is of reduced diameter.

The interior of the tapered portion 83 comprises a seat for a tapered portion 87 of a valve stem 88. Extending forwardly of the taper 87 is a needle 69 of a diameter smaller than that of the valve stem and also smaller than the diameter of the nozzle into which it projects. Mounted fast upon the valve stem is a stop 91 against which a packing ring 92 abuts, the packing being held in place by an abutment ring 93, this arrangement being intended to fit snugly against the interior wall of the body portion 81 to prevent leakage therefrom. The valve stem is spring pressed forwardly into its closed position by means of spring 94 which abuts against ring 93 and also against the interior of a hollow closing cap 95. This particular arrangement also provides a means of continually taking up the wear of the packing since the spring pressure on the loosely mounted ring has a tendency to spread the packing against the inner wall of the valve chamber. The cap 95 is screw threaded internally to cooperate with the screw threaded portion 82 of the valve body 81. The valve stem 88 extends through an aperture in the cap 95 and is screw threaded at its outer end as indicated at 96.

Affixed to the body portion 81 of the valve and at right angles thereto, is the nipple 28 referred to above as being intended to receive the connecting junction of the hose 31 leading to the material supply tank 32.

Distributor assembly

Fitting into the front face of the body member 21 is a guiding member 101. The rear portion of the guiding member 101 is screw threaded as indicated at 102 to cooperate with screw threads in the body portion. The forward portion has an internal taper and an external taper extending from a shoulder 103 that is adapted to abut against the forward face of the body portion of the holder 21.

The internal taper is adapted to cooperate with the tapered portions 83 and 84 of the valve body to guide the fluid valve 81 into position. In this position the channel between 83 and 84 registers with the diagonal aperture 104 in the guide 101. The aperture communicates with the channel 105 that is formed between the guiding member 101 and the body portion 21 just in rear of the abutting shoulder 103 and just forward of the screw threaded portion 102. The channel 105 communicates with the passage 76 through the port 106. Hence air will be admitted to the channel 105, aperture 104, the channel between the members 83 and 84 and through the grooves 85 for purposes to presently appear.

The external taper constitutes a guide for the distributing cap 107 which at its center has an internal taper so proportioned that the end of the guiding member 101 is spaced from the outer edge of the distributing cap 107 so as to form a chamber 108 into which the air is admitted through the grooves 85.

It will be noted that the face of the distributing cap 108 has an aperture therein into which projects the nozzle 86 of the fluid valve 21, but the parts are so proportioned and arranged that 5 the nozzle does not project beyond the distributing cap 107 and is concentric with but spaced from the distributing cap aperture.

Referring to Figs. 9, 10 and 11, it will be noted that the distributing cap 107 is provided at its 10 rear face with a semi-circular groove 111, which groove has communicating therewith at its ends a pair of passages 112 which terminate in enlarged openings 113, one for each passage. The 15 openings 113 are of larger area than the connecting passages 112. The passages 112 and openings 113 are arranged in projections 109 of the cap 107 that terminate in inclined faces 110 through which the openings 113 are made. The 20 faces 110 and openings 113 are respectively arranged at intersecting angles.

Backed upon the cap 107 is a plate 114 which has a central aperture coinciding with the taper of the aperture of the cap 107. The plate 114 may be secured to the cap 107 by screws 115 as 25 shown in Fig. 11, or by any other well known means or may be separate therefrom. The plate 114 is provided with an aperture 116 which communicates with the groove 111 at the center of the arc of the groove. If the groove 111 is of any 30 other configuration the aperture 116 would be located equi-distant from the passages 112.

The cap 107 is provided with an annular flange 117 which cooperates with the flange 118 of a screw threaded retaining ring 119 that is adapted 35 to screw upon the front end of the body portion 21. From Fig. 3 it will be noted that the retaining ring draws the cap 107 and its plate 114 on to the guiding member 101 and that an air space 122 is left between the faces of the holder 21 and 40 the plate 114. The passageway 75 communicates directly with the space 122 to admit air thereto whenever the air valve 25 is in the position indicated in Fig. 5. Then the air will proceed from the space 122 through the aperture 116 into the 45 groove 111, and through the passages 112 and openings 113 to the work.

The object of locating the hole 116 in the center of the arc of the groove 111 or an equal distance from the diametrically oppositely spaced passages 50 112 is to insure an equal distribution of the air to the two openings 113.

Connecting link and regulator

A linkage is provided between the trigger 41 and the fluid valve 21 which permits the trigger 41 to simultaneously actuate the fluid valve and the air valve. This linkage is combined with a regulator for governing the amount of liquid 55 ejected from the fluid valve 21 for the several different positions of the trigger.

This linkage comprises connecting shaft 34, nut 35, and regulating nut 36. The nut 35 is screw threaded and adapted to engage the screw 60 threaded portion 96 of the fluid valve stem 88. Nut 35 is provided with a flanged portion 127 adapted to retain inside thereof the flanged head 128 of the shaft 34. As shown in Fig. 13, the shaft 34 is divided into two halves that are spaced 65 apart to receive the end 42 of the trigger 41 which projects therebetween and the end of the stem 54 of the air valve. The ends of the split shaft 70 34 are screw threaded and are adapted to receive the screw threaded regulating nut 36. The nut 75 36 is hollow and adapted to be guided upon the

projecting end of the air valve 53 as the same moves back and forth.

When the connecting link is secured to the stem 88 of the fluid valve, the nut 35 is screwed until the end 96 contacts with the head 128 of the 5 shaft 34. It will be noted that the projecting end of the trigger 41 not only engages the stem 54 of the air valve but also engages the regulating nut 36 so that the same can be moved rearwardly as the trigger is moved. Thus, the pressure on the 10 regulating nut is transmitted to the shaft 34, the nut 35 and the valve stem 88 to open and close the fluid valve simultaneously with the opening and closing of the air valve. It will therefore be 15 apparent that by causing the nut 36 to take up different positions on the shaft 34, the time of engagement with and therefore the amount of movement by the trigger will determine the amount of movement of the valve stem 88 from its seat 87 which will in turn govern the amount 20 of fluid ejected from the nozzle 86.

There is one other regulating feature illustrated in Fig. 6, wherein are shown the passages 75 and 76 and the connections 73 and 74 thereto from the chamber 55 of the air valve. At times it is 25 desired to regulate air pressure on the fan or wide spray and thereby regulate that spray. This can be accomplished by an adjustment of the plug 131 in the screw threaded portion 132 of the passage 75. As will be apparent from Fig. 6, the plug 30 131 may be moved so as to restrict the opening 73 leading from the chamber 55 into the passage 75 and thus regulate the amount of air admitted to passage 75 which communicates with the openings 113. 35

Operation

Figs. 3, 4 and 5 illustrate the respective positions of the parts of my gun.

It is important to note that in the first position of the trigger 41, illustrated in Fig. 3 in dotted lines and referred to in describing the operation of the air valve where a quantity of air is admitted to the passage 76 and is ejected from the opening about the nozzle 86, there is no 40 movement of the fluid valve because the purpose of this preliminary jet of air is to permit the operator to blow away dust and accumulations on the article to be painted. Hence, Fig. 3 illustrates in full lines the fluid valve as closed and with the spring 94 pressing the stem 88 forward against the tapered seat 87, and spring 66 pressing 45 valve head 63 against its seat 62.

When the trigger has been moved to its second 50 operative position illustrated in Fig. 4, a full flow of air is admitted to the passage way 76 from the chest 55 through the ports 58. From passage 55 76 air is admitted to channel 105, and through passage 104, communicating channel and grooves 85 to the chamber 108 and outlet aperture surrounding the nozzle 86. The trigger has moved the regulating nut and connecting link 34 rearwardly so as to remove the valve stem 88 from its seat 87. The material being under pressure, will be ejected in a circular or cone shaped stream 65 about the nozzle 86. By this arrangement the material is ejected through the nozzle and the air is ejected from an annular passage surrounding the material jet, thus commingling with the material to atomize it and eject it with sufficient 70 force for the purposes for which the gun is intended. This arrangement forms what is termed the cone or narrow spray.

In Fig. 5 is shown the third position in which the trigger has moved further to the rear. This 75

has moved the air valve to a point where air is admitted to both the passages 75 and 76. Air is admitted to passage 75 from the chest 55 through channel 64 on the stem 54, and passage 73. From 5 passage 75 air passes directly to chamber 122 and through aperture 116, groove 111 and passages 112 to outlet openings 113.

In this position the stem 88 has been moved further so that the maximum amount of material 10 is being ejected through the fluid valve and formed into a cone spray as explained in Fig. 4. However, by reason of the arrangement of intersecting jets of air from the openings 113, the normal 15 cone shaped spray is diffused when the intersecting jets meet changing the shape of the spray to a wide, flat, fan-shaped spray.

The size of the flat spray may be controlled by adjusting the regulating nut 131.

The openings 113 are larger than communicating 20 passages 112. By creating a sudden drop in pressure at the openings 113 two important results are obtained, first, the jets of air are broadened so as to provide a broader resultant spray, and second, the lowered pressure eliminates 25 the vortex of material that would otherwise have a tendency to build up on the face of the cap and either obstruct the spray passages or result in the distortion of the spray.

It will be apparent that an operator can, at 30 will, select the use of a narrow spray (Fig. 4) and a wide spray (Fig. 5) by simply releasing and compressing the trigger into the positions shown in Figs. 4 and 5 respectively. This is brought about not only by the arrangement of the air 35 valve and fluid valve in axial alignment, but also by the arrangement of the connecting link so that a single operation of the trigger actuates both valves. Likewise, an operator can select between an air jet only and a material jet by 40 operation of the trigger.

Removability of valves

An important feature of my improved gun is the ready removability of the fluid valve and the 45 air valve from the holder 21.

It will be noted that the body portion 21 is provided with a hood 30, which is open at its bottom and has an enlarged portion 134 that communicates with the main slot 135. The slot 50 135 more or less snugly fits the rounded body 81 of the fluid valve and substantially covers the same except for the downwardly projecting nipple 28. From Fig. 3 it will be noted that the enlarged portion 134 is provided with a flange 136 55 which is semi-circular and adapted to receive the flange 137 of the cap nut 95.

Assuming that the parts are in the position shown in either Figs. 3, 4 or 5, the fluid valve would be removed as follows:

60 Unloosen the nut 35 from the screw threaded portion 96 of the valve stem 88, and also unloosen the nut 95 from close engagement with the flange 136. The fluid valve is then readily taken out of the holder 21 without removing the same from 65 its connection with the hose 31 to which it may be connected and without disturbing any portion of the distributor assembly.

A new fluid valve 27 affixed to its hose 31 may be promptly inserted in the slot 135 of the hood 70 30 with the flange 137 of its nut 95 positioned in the groove formed by the flange 136 and the tapered portion of the fluid valve projecting into the distributor assembly. The nut 35 is then screwed into place. After this operation, the 75 fluid valve may then be forced forwardly and

affixed securely in position in the holder by tightening the nut 95 so as to bring the flange 137 into engagement with the flange 136.

By tightening the nut 35, the tip 89 of the stem 88 of the fluid valve is forced more firmly into its forward position. By tightening the cap nut 95, the fluid valve is forced forwardly into the guiding member 101 so as to properly position the nozzle of the fluid valve in its concentric relation with the center hole of the distributor 10 cap and bring the grooves 85 into proper position.

When the guiding member and the distributor 15 cap 107 are positioned in concentric relation with the nozzle of the fluid valve the proper arrangement of air jet is provided and the retaining ring will maintain the parts in that position.

By the arrangement of the nozzle extending into the distributor cap and the arrangement for distributing the air in the several jets, the 20 material is carried away from the face of the cap and not permitted to build up thereon. Hence, since all the parts that come in contact with the material are removed when the fluid valve is removed it is practical, with my improved 25 gun, to continue to reuse the guiding member 101, distributor cap 107 and retaining ring 119 even with changes of colors or changes of materials.

The air valve is removed by merely unscrewing 30 the same from the holder 21.

By the arrangement of a cartridge type of air valve, one air valve may be removed and replaced by another cartridge valve in the event of the breakage of a spring or the clogging of the 35 passages, so as to interfere with the operation of the gun.

Certain features of the structure disclosed herein are not intended to be covered by the appended claims, but are described and claimed in 40 my copending application Ser. No. 310,418, filed concurrently herewith, especially the air valve shown and described herein.

Modifications may be made in the arrangement and location of parts within the spirit and scope 45 of my invention, and such modifications are intended to be covered by the appended claims.

I claim:

1. A gun of the character described comprising a body portion, a movable trigger mounted 50 for movement forwardly and rearwardly, a connection from the gun to a source of material supply, a connection from the gun to a source of air under pressure, means whereby a jet of air free from material may be projected from said 55 gun, means whereby a narrow jet of material may be projected from said gun, means whereby a wide jet of material may be projected from said gun, and connections whereby an operator may select either jet by rearward movement of said 60 trigger.

2. A gun of the character described comprising a body portion, a distributor thereon, a movable member mounted for movement forwardly and rearwardly, a connection from the gun to 65 a source of material supply, means whereby a round jet of material may be projected from said gun through said distributor, and means whereby a flat jet of material may be projected from said gun through said distributor, and connections whereby an operator may select either 70 jet by rearward movement of said member.

3. A gun of the character described comprising a body portion, a connection from the gun to a source of material supply, a connection from 75

the gun to a source of air under pressure, means whereby a jet of air free from material may be projected from said gun at will, means whereby jets of material of varying sizes may be delivered from said gun, and a control member for said means operable so that an operator may vary the size of the jet of material at will and select between air and material jets at will, the control member being mounted for movement in one plane only.

4. A gun of the character described comprising a body portion, a connection from the gun to a source of material supply, a valve controlled connection from the gun to a source of air under pressure, means whereby a variety of jets of material may be projected successively from said gun, means whereby a jet of air free from material may be projected from said gun, a spring normally urging the air valve closed, and a control member acting against said spring whereby an operator may select between the air and any of the plurality of material jets at will.

5. A gun of the character described comprising a body portion, a connection from the gun to a source of material supply, an air valve, connections therefrom whereby either a round jet or a flat jet of material may be projected from said gun, and a control member to actuate said air valve and also to select between said jets at will, the control member being mounted for movement in one direction for both operations.

6. A gun of the character described comprising a body portion, connections from the gun to a source of material supply and to a source of air under pressure, means including a valve whereby jets of material of different contours may be successively projected from said gun, and a control member mounted for movement in one direction only to actuate said valve whereby an operator may select between said jets at will.

7. A gun of the character described comprising a body portion; a liquid valve having a body, a guiding portion thereon, and a nozzle; and a distributor assembly comprising a member having an aperture adapted to receive said nozzle in spaced relation, and a guiding member having a screw-threaded connection with said body portion and positioning the valve with respect to the distributor so as to provide an enlarged chamber in back of the distributor, and means connecting the same with the space about said nozzle.

8. A gun of the character described comprising a body portion; a liquid valve having a body, a guide thereon, and a nozzle; and a distributor assembly comprising a member having an aperture adapted to receive said nozzle in spaced relation, and a member having a screw-threaded connection with said body portion and cooperating with said guide to position the valve body and also to guide and position the distributor member in spaced relation to the valve body to form air chambers about said nozzle and in back of said distributor.

9. A gun of the character described comprising a body portion; a liquid valve having a body, a guide thereon, and a nozzle; a connection from said gun to a source of air supply; a distributor assembly comprising a member having an aperture, a member adapted to cooperate with said guide to position said nozzle within said aperture but spaced therefrom, and also adapted to position the distributor member to form a plurality of enlarged chambers, and additional apertures in said distributor member arranged at intersect-

ing angles; and means for supplying air to the apertures in the distributor member.

10. A gun of the character described comprising a body portion; a liquid valve having a body, a guide thereon, and a nozzle; a connection from said gun to a source of air supply; a distributor assembly comprising a member having an aperture, a member adapted to cooperate with said guide to position said nozzle within said aperture but spaced therefrom, and also adapted to position and space the distributor member so as to form a chamber in back of said distributor member closed from said aperture, and additional apertures in said distributor member arranged at intersecting angles and in communication with said chamber; and means for selectively supplying air to the apertures in the distributor member.

11. In a gun of the character described, a body portion, an air valve having an air chest, communications therefrom to a source of air under pressure, valve closing means, a spring normally urging the valve to closed position, a plurality of sets of ports in communication with said air chest through said closing means, communications from said ports to separated outlet openings in said body portion, and means mounted on said body portion for actuating said valve against the action of said spring and also adapted to selectively admit air to the communications to said outlet openings.

12. In a spraying device, a spray head adapted to be connected with a source of supply for liquid and with a source of supply for air under pressure, having a main air outlet arranged to cause a jet of atomized liquid to be discharged from said spray head and also having auxiliary air outlets arranged to control the shape of said jet of atomized liquid, a single distributing valve to selectively control the flow of air to said main outlet and said auxiliary outlets, a spring urging the valve to position to shut off the air supply, and means acting against the spring for adjusting said distributing valve.

13. In a spraying device, a supporting structure, a spray head carried by said structure, adapted to be connected with a source of supply for liquid and with a source of supply for air under pressure and having an outlet for liquid and an outlet for air arranged to cause a jet of atomized liquid to be discharged from said spray head, said spray head also having auxiliary air outlets to control the shape of said jet of atomized liquid, a valve to control the flow of liquid through said liquid outlet, separate conduits leading from the respective air outlets to the rear end of said supporting structure, a valve arranged at the rear end of said supporting structure to selectively control the flow of air through said conduits and also to shut off all air to the air outlets, and an actuating device connected with both of said valves, and movable rearwardly for operating said valves and for selectively controlling the flow of air through said conduits.

14. In a spraying device, a spray head adapted to be connected with a source of supply for liquid and with a source of supply for air under pressure, having a main air outlet arranged to cause a jet of atomized liquid to be discharged from said spray head and also having auxiliary air outlets arranged to control the shape of said jet of liquid, means for selectively controlling said main air outlet and said auxiliary air outlets, a single actuating device for said controlling means which is operable to cause air from said source of supply to be delivered either to said main air outlet

alone or to said main air outlet and said auxiliary air outlets, and a mounting for the actuating device permitting the same to move rearwardly and forwardly only in effecting said operations.

- 5 15. A gun of the character described comprising a body portion, a connection from the gun to a source of material supply, a connection from the gun to air under pressure, a movable trigger, a pair of stops cooperating with the movable 10 trigger, and means whereby when the trigger is moved into engagement with one of said stops a round spray of material is projected from said gun and whereby when the trigger is moved into engagement with the other of said stops a flat 15 spray of material is projected from said gun, said stops being so arranged that the operator can instantly change from the round spray to the flat spray without interrupting the operation of the gun.
- 20 16. A gun of the character described comprising a body portion, a connection from the gun to a source of material supply, means whereby jets of material of varying form may be delivered from said gun, and a control member for 25 said means whereby an operator may control the operation of said gun and also vary the form of

the jet of material at will, said control member operating in one plane only.

17. Apparatus for spraying liquids or other material, having a spraying head at which occurs, alternatively, round and fan shaped sprays, a 5 control valve coacting with a seating in the spraying head for the material to be sprayed, a frame member carrying the spraying head and having a hand grip, a trigger movable towards the hand grip for opening the material control valve, an air feed conduit for delivering air to the spraying head for producing a round spray, an air valve controlling the flow of air through such latter conduit, an air feed conduit for delivering air to the spraying head for effecting a fan shaped 15 spray, an air valve for controlling the flow of air through such latter conduit, and means whereby the said trigger successively opens the said air valves as it is moved towards the hand grip, so that the first mentioned air valve is first opened 20 during the initial movement of the trigger towards the hand grip, and so that on the continued movement of the trigger in the same direction the second mentioned valve is opened.

25 ALFRED W. SMART.
